E. W. Marshall
ATTORNEY

UNITED STATES PATENT OFFICE.

CHARLES C. TOMKINSON, OF PLAINFIELD, NEW JERSEY, ASSIGNOR TO J. EDWARD OGDEN, OF MOUNTAINVILLE, NEW YORK.

DOOR MECHANISM.

Application filed February 29, 1924. Serial No. 696,108.

This invention relates to doors and particularly to doors of the type used in warehouses, pier sheds or like structures.

Doors of the character specified are usually made in sections and to open the doors, the sections are raised to overlapping position and are then swung laterally or inwardly to inclined position, thus conserving headroom. Such doors are very large and heavy in construction and to facilitate the operation thereof, counterweighting means is provided.

In one form of construction, tracks are used to cooperate with rollers or lugs on the door to swing the door sections inwardly and to guide and support the sections as they are moved to inclined or horizontal position. Such tracks have curved portions for swinging the sections and substantially horizontal portions for supporting and guiding the sections after they have been swung from the vertical into inclined position.

In order to effectively counterbalance doors of the type specified, there are three different stages or conditions which must be met during the opening and closing of the door.

One counterbalancing condition is encountered when the lower section is raised to a position overlying the upper section.

The second stage is encountered when the two sections are traveling in the curved portion of the track and are swinging out of the vertical plane to a position in which the upper end of the combined sections are disposed on the horizontal portion of the track.

The third stage is encountered as the upper ends of the combined sections travel on the horizontal portion of the track and the door is swung to its wide open or inclined position.

During the first stage when the lower section is rising to a position overlying the upper section, the counterweight required is equal to the weight of the lower section.

During the second stage the counterweight required varies from the full weight of the combined sections at the start to one half of the weight of the combined sections at the end of this stage when the upper ends of the combined sections are supported on the horizontal portion of the track.

During the third stage when the upper ends of the combined sections travel on the

horizontal portion of the track the counterweight required is equal to one half of the weight of the combined sections.

To meet these conditions it is necessary that counterweighting means be so connected to the door sections that the counterweighting effect will vary in accordance with the requirements and will counterweight the lower section during the first stage and the combined sections during the second and third stages and in counterweighting the combined sections, the counterweighting effect should be reduced from a counterweight equal to the full weight of both sections to a counterweight equal to one half of the combined sections.

This invention has for its salient object, therefore, to provide counterweighting mechanism for doors so constructed and arranged that a substantially perfect counterbalance will be effected in all positions of movement of the door sections.

Another object of the invention is to provide a counterweighting mechanism for doors so constructed and so connected to the doors that the counterweighting effect will be varied in accordance with the requirements therefor during the opening and closing movements of the door.

Further objects of the invention will appear from the following specification taken in connection with the drawings, which form a part of this application, and in which—

Fig. 1 is a sectional elevation of the door constructed in accordance with the invention, the door sections being shown in closed position.

Fig. 2 is a view similar to Fig. 1 but showing the lower section raised to a position overlying the upper section.

Fig. 3 is a view similar to Figs. 1 and 2, but showing the combined sections after they have finished their travel in the curved portion of the track and have reached the horizontal portion of the track.

Fig. 4 is a view similar to Figs. 1 to 3, but showing the combined sections in their wide open position.

Fig. 5 is an elevational view partly broken away showing the use of a separate counterweight for each section instead of a single counterweight for both sections.

Fig. 6 is a transverse sectional view taken substantially on line 6—6 of Fig. 1.

Fig. 7 is a sectional view taken substantially on line 7-7 of Fig. 1, and

Fig. 8 is an elevational view partly in section and partly broken away showing diagrammatically the method by means of which the overhead sheaves are located with reference to the point of attachment of the counterweight cable to the upper door section.

10 The invention has been worked out in connection with a door comprising two sections and the gist of the invention consists in so connecting counterweighting means to the upper and lower door sections that the 15 counterweighting effect will conform to the counterweighting requirements during all portions of the cycle of operation of the door sections. In order to accomplish these results and to vary the counterweighting effect as the requirements vary, the horizontal 20 and vertical components of the counterweighting force are varied or varyingly neutralized in accordance with the counterweighting requirements during the movement 25 of the upper ends of the door sections around the curved portions of the tracks and are fully neutralized during the travel on the horizontal portions of the tracks. It has been found this can be accomplished by 30 properly coordinating the locations of the pivot for the sheave over which the cable passes that connects the counterweight to the upper door section and the point of connection of this cable to the upper door 35 section. It has been determined that the point of attachment of the cable to the upper door section which gives this coordination, travels substantially in the path of an involute curve described about the periphery of the sheave over which the cable passes 40 while the upper ends of the door sections travel along the horizontal portion of the track. When this point has been located properly with reference to the pivot of the 45 sheave, there will be no motion of the sheave during the movement of the upper ends of the door sections along the horizontal portion of the track and no movement of the chain passing over the sheave to the counterweight and consequently no counterweighting effect. The problem is, therefore, solved by so relatively locating the pivot of the sheave and the point of connection of the cable to the upper door section that the 50 point of attachment to the cable of the upper door section will travel in an involute curve described about the periphery of the sheave. Another way of stating this problem is that when the cable is connected to the 55 proper point on the upper section, the stress in the cable is resolved into vertical and horizontal components whose moments are equal and opposed so that one fully neutralizes the other during the travel on the 60 horizontal portion of the track. Further de-

tails of the invention will appear from the following description.

In the drawings there is illustrated a two section door comprising a lower section 10 and an upper section 11. The lower section 10 has secured to its edges in brackets 12, rollers 13, which as the door is raised engage vertical guiding strips or tracks 14 secured in any suitable manner to the wall of the building. The upper section 11 is provided 75 as shown in Fig. 7 with inwardly extending flanges 15, which overlap outwardly extending portions 16 of the lower door section, thus guiding this section in its upward movement. The lower section has secured thereto lugs 17 adapted to engage the under surface of the lower end 18 of the upper section 11 when the lower section has been moved to a position overlapping the upper section as shown in Figs. 2, 3 and 4.

In the particular embodiment of the invention shown, the means for moving the doors inwardly after the lower section is elevated to a position overlying the upper section, comprises a pair of guiding and supporting tracks 19 secured in any suitable manner to the frame structure of the building and having grooves 20 in which are positioned rollers or lugs 21 mounted on the side edges of the upper door section 11. The 90 tracks 19 have curved portions 22 for "breaking in" the door or swinging the door out of the vertical plane and substantially horizontal portions 23 for guiding the doors as they are swung to inclined position and for assisting in supporting the doors after the rollers 21 reach the horizontal portions of the tracks.

As above stated, in order to effectively counterbalance the doors in all positions of their movement one half of the counterweighting effect should be available during the movement of the lower door to a position overlying the upper door section and one half of the counterweighting effect should be available after the doors have reached the position shown in Fig. 3, namely, the position in which the rollers 21 have reached the horizontal portion 23 of the tracks. During the movement of the doors from the position shown in Fig. 2 to the position shown in Fig. 3, the counterweighting effect should be varied from the full counterweighting effect at the start to one half of the counterweighting effect at the completion of this portion of the movement.

The counterweighting mechanism by means of which these results are accomplished will now be described. In the embodiment of the invention shown in Figs. 1 to 4 inclusive a single counterweight or a pair of single counterweights is provided for both door sections although as shown in Fig. 5 a separate counterweight could be provided for each door section. When both

sections weigh substantially the same, the single counterweight or the pair of single counterweights is preferable. In this construction, a counterweight 30 has secured thereto a sheave 31 around which passes a cable 32. The cable 32 has one length thereof extending around a sheave 33 mounted on a shaft or pivot 34 at a predetermined fixed point and the end of this length of cable is connected to the lower door section 10 adjacent to the lower end thereof as shown at 35. The other length of the cable 32 passes around a sheave 36 loosely mounted on the pivot or shaft 34 and the end of this length of cable is connected to the upper door section at a suitable point such as the point 37, the location of which will be hereinafter described. Sheaves 33 and 36 are preferably provided at each end of the shaft 34 and a counterweight 30 is connected to the door sections at both side edges thereof. Any suitable operating means for hoisting the door sections may be utilized such, for example, as mechanism for rotating sheaves 33.

Since one end of the cable 32 is connected to the lower door section and since during the first stage of movement of the door sections the upper section does not move, it will be evident that one half of the weight of the counterweight 30 will be effective during the movement of the lower section from the position shown in Fig. 1 to the position shown in Fig. 2.

Moreover, since the point 37 of connection of the cable 32 to the upper door section 11 is located between the upper and lower edges thereof, preferably above the center, the horizontal and vertical components of the counterweight force will be varied during the movement of the door sections from the position shown in Fig. 2 to the position shown in Fig. 3 as the point 37 moves outwardly away from the initial vertical plane of the door section 11. Therefore, the counterweight force acting on the door sections will be decreased during the movement of the door sections around the curved portion of the track.

The real problem to be solved, therefore, is to so locate the point 37 with reference to the pivot 34 that the effect of the counterweight on the door sections will be reduced to one half the full counterweighting effect when the sections reach the position shown in Fig. 3 and during their movement from this position to the wide open position shown in Fig. 4. In order to accomplish this, the sheave 36 around which the counterweight cable passes to the upper door section should remain stationary after the doors have reached the position shown in Fig. 3. If this is effected, then the counterweight will act only through the connection to the lower door section.

One method of accomplishing this result last stated is shown in Fig. 8 and it has been found that for each location of the point 37 of connection between the cable 32 and the upper door section, there is a corresponding correct location for the pivot 34 of the sheave 36. Since the sheave 36 is not to rotate during this period of movement of the door sections, it will be obvious that the length of cable between this sheave and the upper door section should unwind from the periphery of the sheave. This being so, the point of connection to the upper door section must move in an involute described about the periphery of the sheave 36 or approximately in such a path.

The curve X shown in Fig. 8 is in an involute curve generated around the periphery of the sheave wheel 36. By plotting the various positions taken by a point such as 37 on the upper door section when this door section moves from the position shown in Fig. 3 and diagrammatically in Fig. 8 to the wide open position shown in Fig. 4 and diagrammatically in Fig. 8, it has been determined that these points lie in a curve which can be located on the involute curve X provided the pivot 34 of the sheave is properly located and correlated to the particular point chosen for the counterweight cable connection.

Referring to Fig. 8, the point M is located substantially at the center of the combined door sections and the points N, O, P and Q are spaced apart equal distances above the point M. The curves M—M, N—N, O—O, P—P and Q—Q represent the paths of travel of the points M, N, O, P and Q as the door sections move from the positions shown in Fig. 3 to the position shown in Fig. 4.

The points M', N', O', P' and Q' represent the correct corresponding positions for the pivot 34. These points, M', N', O', P', and Q' were found in the following manner. To locate the point M' the involute curve was superimposed on the line M—M and rotated until a portion of this curve, as shown in Fig. 8, was found to substantially coincide with the curve M—M generated by the point M as the door was moved from one position shown in Fig. 8 to the other position shown therein. When a portion of the involute curve coincided in the manner set forth with the curve M—M, the center of the involute located the point M'. The points N', O', P' and Q' were similarly located and in each instance it was noted that no other portion of the curve could be made to coincide with the generated curve M—M, N—N, O—O, P—P and Q—Q. The portions of the involute which were found to coincide with the generated curves are indicated on the involute by the letters M—M, N—N, O—O, P—P and Q—Q.

In practice the sheave wheel 36 must always be located in some position at or above the plane of the horizontal portion of the track and, therefore, the point of connection 37 must be located somewhere between the center and the upper end of the combined door sections and for each point of attachment so located a corresponding point of location for the pivot 34 can be found.

10 It is well known in this art that a door of the character described has considerable friction in operation and that a practical balance can always be obtained by an approximation of the correct theoretical balance.

15 It should be understood, therefore, that the invention is not limited to an exact point of attachment 37 for a given sheave position or a given position of the pivot 34 but that points located adjacent these points will give a practical balance.

It should also be understood that the invention is not limited to the use of a single counterweight for balancing both door sections but that a separate counterweight may be used for each door section, if desired, as shown in Fig. 5. In this case, each counterweight should correspond in weight to the weight of the door section to which it is connected and the point of connection 37 can be varied to suit the circumstances. For instance, if the lower section is considerably heavier than the upper section, then the connection 37 should be made at a point to overcome this condition during the movement of the door sections between the positions shown in Fig. 8. In this case, as the counterweight would weigh more than half of the combined sections during the second and third periods, the connection should be above the neutral point or above the point at which the counterweighting force exerted through the cable passing over the sheave 36 is neutralized. In other words, for the location of the sheave at M', N', O', P' or Q', the connection of the cable to the door section should be above the point M, N, O, P, or Q. Under this condition, the sheave wheel 36 will rotate in an anti-clockwise direction during the movement of the door sections through their third stage of opening movement.

From the foregoing description, it will be seen that a method has been provided for accurately determining the correct locations of the pivot for the sheaves and the point of connection of the cable to the upper door section and that with these two points so determined the door will be effectively counterbalanced in all positions of its movement.

Although certain specific embodiments of the invention have been particularly shown and described, it will be understood that the invention is capable of modification and that changes in the construction and in the arrangement of the various cooperating parts

may be made without departing from the spirit or scope of the invention, as expressed in the following claims.

What I claim is:

1. Door mechanism comprising a plurality of door sections movable vertically and laterally, track means for guiding said sections laterally, said track means having an inclined portion and a substantially horizontal portion, counterweighting means for said door sections connected to the lower door section adjacent the lower end thereof and to the upper door section intermediate the upper and lower ends thereof, and sheaves disposed above the path of movement of the door sections and over which the connecting cable passes from the counterweighting means to the door sections, one of said sheaves being so located that the path of movement of the point of connection of the cable to the upper door section will substantially coincide with a portion of an involute curve generated around the periphery of the sheave wheel from which the cable passes to the upper door section when the upper ends of the door sections are being guided along the horizontal portion of the track.

2. Door mechanism comprising an upper door section and a lower door section movable vertically and laterally, said lower section being movable to a position overlying the upper section and both of said sections being subsequently movable in unison vertically and laterally to inclined position, means for guiding the upper ends of said sections in an inclined path and in a substantially horizontal path and counterweighting means operatively connected to said lower door section adjacent the lower end thereof and to said upper door section intermediate the upper and lower edges thereof, said counterweighting means being connected to the sections by flexible means and sheaves intermediate said counterweighting means and said door sections for supporting and guiding said flexible means, one of said sheaves being so located relative to the point of connection of the flexible means to the upper door section that said point of connection to the upper door section will travel substantially in an involute path about the periphery of the sheave wheel over which the flexible means passes to said upper door section when the upper ends of the door sections are guided in a substantially horizontal path.

3. Door mechanism comprising an upper door section and a lower door section movable vertically and laterally, said lower section being movable to a position overlying the upper section and both of said sections being subsequently movable in unison vertically and laterally to inclined position, means for guiding the upper ends of said

sections in an inclined path and in a substantially horizontal path and counterweighting means operatively connected to said lower door section adjacent the lower end thereof and to said upper door section intermediate the upper and lower edges thereof, said counterweighting means being connected to the sections by flexible means and sheaves intermediate said counterweighting means and said door sections for supporting and guiding said flexible means, the sheave over which the flexible means passes to the upper door section being so located with reference to the point of connection of said flexible means to said upper door section that said sheave will remain substantially stationary during the travel of the upper ends of the door sections in the substantially horizontal path.

4. Door mechanism comprising a plurality of door sections movable vertically and laterally, track means for guiding said sections laterally, said track means having an inclined portion and a substantially horizontal portion, counterweighting means for said door sections connected to the lower door section adjacent the lower end thereof and to the upper door section intermediate the upper and lower ends thereof and sheaves mounted on a pivot disposed above the path of movement of the door sections and over which the connecting cable passes from the counterweighting means to the door sections, the sheave over which the cable passes to the upper door section being so located relative to the point of attachment of the cable to the upper door section that said sheave will remain substantially stationary during the travel of the upper ends of the door sections along the horizontal portion of said track means.

5. Door mechanism comprising a plurality of door sections movable vertically and laterally, track means for guiding said sections laterally, said track means having an inclined portion and a substantially horizontal portion, counterweighting means for said door sections connected to the lower door section adjacent the lower end thereof and to the upper door section at a point above the center thereof, and sheaves disposed above the path of movement of the door sections and over which the connecting cable passes from the counterweighting means to the door sections.

6. Door mechanism comprising a plurality of door sections movable vertically and laterally, track means for guiding said sections laterally and guiding and supporting the sections as they move to inclined or substantially horizontal position, and counterweighting means comprising a counterweight, a sheave on said counterweight, a pair of sheaves disposed above the path of

travel of the door sections and a cable passing around the counterweight sheave and over the sheaves and having one end connected to the lower door section adjacent the bottom thereof and the other end connected to the upper door section above the center thereof.

7. Door mechanism comprising a door movable vertically and laterally, track means for guiding the door laterally, said track means having an inclined portion and a substantially horizontal portion, counterweighting means for said door connected to the door intermediate the upper and lower ends thereof and sheaves disposed above the path of movement of the door and over which the counterweighting cable passes from the counterweighting means to the door, the pivot of one of said sheaves being so located that the path of movement of the point of connection of the cable which passes over said sheave to the door intermediate the upper and lower ends thereof will substantially coincide with a portion of an involute curve generated around the periphery of said sheave when the upper end of the door is being guided along the horizontal portion of the track.

8. Door mechanism comprising a door movable vertically and laterally, track means for guiding the door laterally, said track means having a portion for guiding the door in a path in which the upper end of the door has a vertical component of movement and in a path in which the upper end of the door moves in a substantially horizontal path, counterweighting means for the door connected to the door adjacent the lower end thereof and intermediate the upper and lower ends thereof, a sheave mounted on a pivot disposed above the path of travel of the door and over which the connecting cable passes from the counterweighting means to the intermediate point on the door, said sheave being so located relative to said intermediate point that the sheave will remain substantially stationary during the travel of the upper end of the door along the horizontal portion of the track means.

9. A door comprising upper and lower sections arranged to move together vertically and laterally, track means for guiding the sections laterally, a counterbalancing mechanism comprising a counterweight, and a connecting means between the counterweight and the upper door section arranged to produce an upward pull on the upper door section, and means for neutralizing said upward pull at a predetermined part of the movement of the two door sections.

In witness whereof, I have hereunto set my hand this 13th day of February, 1924.

CHARLES C. TOMKINSON.
